Howard Meyer,
By their Attorney, Geo. W. Meier

UNITED STATES PATENT OFFICE.

MARTIN MEYER AND HOWARD MEYER, OF NEW YORK, N. Y.

SYRINGE.

1,231,772.

Specification of Letters Patent.

Patented July 3, 1917.

Application filed January 29, 1917. Serial No. 145,113.

To all whom it may concern:

Be it known that we, MARTIN MEYER and HOWARD MEYER, both citizens of the United States, and residents of the borough of Manhattan, city, county, and State of New York, have invented certain new and useful Improvements in Syringes, of which the following is a specification.

Our improvements are applicable to syringes generally, although designed particularly for those used for aural and other organic treatments where cleanliness and sanitation are of especial importance. The invention consists in the specific construction and arrangements of parts described and claimed, a distinctive feature being the provision of an outer casing for the main cylinder which not only strengthens and reinforces the latter, and protects it from injury from contact with extraneous objects, but also acts as a means of drainage and discharge for leakage, all as hereinafter fully set forth.

In the accompanying drawings,
25 Figure 1, is an elevation of our improved syringe;

Fig. 2, is a central longitudinal sectional elevation thereof;

Fig. 3, is a front end view;

30 Fig. 4, a transverse section taken upon the plane of line 4-4, Fig. 2.

The main or piston cylinder C, is formed with an exterior jacket C', also preferably cylindrical and concentric with said piston cylinder C,—the two being spaced apart so as to form an annular passage or compartment c, communicating with the piston cylinder C, through the medium of a series of holes c', c'. These ports or openings c', c', are situated near the rear extremities of both cylinders C, C', adjacent to the annular shoulder c², by means of which the two cylinders are soldered or otherwise permanently and rigidly secured together. The cylinders may further be connected by webs c²², near their forward ends to stiffen and reinforce the structure, these webs however being only incidental and spaced apart so as not to interfere with the drainage of the space c, between the tubes.

The inner cylinder C, protrudes beyond the annular closure shoulder c², the extension c³ being peripherally threaded for engagement with the female screw thread a, formed for the purpose on the flange of the

rear cap A, through which the piston rod p, extends,—said rear cap A, being formed with a packing box a', to prevent leakage around said piston rod p.

The outer extremity of the piston rod p, 60 is formed with a finger loop p', to facilitate manipulation; and finger loops a², a², may also be formed on the rear cap A, for a like reason, they being available as affording a purchase when the piston rod is being 65 driven inward to cause the piston P, to expel through the induction and discharge duct c⁴, the contents of the cylinder from between the outer face of the piston P, and the front end c⁵, of said inner cylinder C,—said inlet 70 and discharge duct c⁴, forming an integral part of said cylinder end c⁵.

The front end of the outer cylinder or jacket C', is screw threaded and is closed by a screw cap B, which is also female screw 75 threaded centrally to receive the threaded extremity of the inlet and discharge duct c⁴, the axis of which coincides with the central passage b, in the front end screw cap B, which passage b, extends through the nipple 80 b', to which syringe tip s, is attached.

A packed piston being undesirable where acid and other chemical solutions are used, and where perfect sanitation is a desideratum, we make our piston P, in the form 85 of a hollow cylinder, hermetically sealed at both ends. The lack of packing however obviously admits of more or less leakage around the piston, which is why we provide for drainage through the space c, between 90 the jacket C', and the main cylinder C, said drainage escaping through the holes b², formed for the purpose in the front cap B.

In charging the syringe is held in a substantially vertical position over the vessel containing the liquid or solution to be used in the treatment of the patient, and, the piston having been previously pushed forward to expel the last preceding charge, is drawn upward by means of the rod p, and loop p', thereby sucking in a fresh charge through the syringe tip s, nipple b', and duct c⁴. This upward or retractile stroke of the piston forces any leakage or drainage that may have collected in the main cylinder C, above or to the rear of the piston P, out through the ports c', into the space c, between the two cylinders, from which space c, this drainage escapes through the ports b², in the end cap B, back into the supply vessel below.

By thus disposing of the leakage it cannot drip on clothing or otherwise become objectionable.

When the piston is advanced to expel the liquid through the duct c^4 , nipple b' , and tip s , any leakage around the piston P , collects in the space between it and the rear cap A , to be in turn expelled through the drain space e , when the piston is retracted 10 as above set forth.

It will thus be seen that our auxiliary cylinder or jacket fulfils a triple function in that it reinforces and strengthens the syringe as a whole; protects the inner main cylinder 15 from indentation or injury by reason of contact with extraneous objects; and affords a drainage passage for the elimination of leakage, etc.

With an unpacked piston such as is used in 20 syringes of this class the protection of the main cylinder against injury or indentation is important, since even a slight internal depression in the main cylinder C , would be sufficient to cause binding of the piston and 25 interfere with the utility of the device; while the additional strength and stability afforded by the duplex structure of cylinders adds materially to the life of the syringe and insures it against rough usage.

30 The acidulated and medicated solutions that are used in the treatment of certain diseases and affections renders the elimination of leakage during use an important factor, since otherwise the clothing of patient or attendant are apt to suffer serious damage.

What we claim as our invention and desire to secure by Letters Patent is,

1. A syringe of the character designated, comprising a main cylinder, a protecting 40 jacket surrounding the same, said main cylinder having at one end an annular clo-

sure shoulder and at the other end webs on the exterior of the cylinder contacting with the said jacket and serving as reinforcements, a piston and accessories, the cylinder 45 having drain ports, a cap on the front end of said jacket provided with drain holes and a discharge opening and a nozzle on the main cylinder projecting into said discharge opening.

2. A syringe of the character designated, comprising a cylinder having a connecting duct extending from one end thereof, a piston and its accessories, an outer protecting jacket spaced therefrom and communicating therewith, a front cap having drain holes and a central passage and an exterior nipple, and an interior socket to receive said connecting duct on the adjacent end of said cylinder.

3. A syringe of the character designated, comprising an inner main cylinder formed at its forward end with an induction and discharge duct, a cap closing the rear end of said main cylinder and formed with a packing box for the piston rod, said piston rod and the piston attached thereto, an external cylinder concentric with said main cylinder rigidly attached thereto and communicating with the interior thereof, and a front end 60 cap closing the forward end of said external cylinder and formed with an opening therethrough and a nipple connecting with the induction and discharge duct on the front end of the inner main cylinder, for the purpose set forth.

MARTIN MEYER.
HOWARD MEYER.
